UNITED STATES PATENT OFFICE.

LESLIE R. HARSHA, OF CHICAGO, ILLINOIS, ASSIGNOR TO THE L. R. HARSHA MANUFACTURING COMPANY.

DESIGN FOR A CURTAIN-POLE.

SPECIFICATION forming part of Design No. 22,186, dated January 31, 1893.

Application filed January 6, 1893. Serial No 457,555. Term of patent 3½ years.

To all whom it may concern:

Be it known that I, LESLIE R. HARSHA, a citizen of the United States, residing at Chicago, county of Cook, and State of Illinois, have 5 invented and produced a new and original Design for a Curtain-Pole, which is fully set forth in the following specification, reference being had to the accompanying drawings, forming a part thereof, wherein—

10 Figure 1 is an elevation and Fig. 2, a section of a curtain pole of my design.

This design relates to poles or rods which, by reason of their adaptation to the use of supporting curtains are commonly called 15 "curtain poles."

This design relates to the configuration of the pole in cross-section, said configuration being the same at all points of the length of the pole. The characteristic of this cross- 20 sectional design is, in general, circular, alter-

nate and substantially equal segments of the cylindrical surface of the pole being longitudinally reeded or corrugated, the other alternate segments being left plain and of the general cylindrical curvature. The customary cord groove *c*, wherever located, slightly mutilates but does not alter the design. 25

I claim:—

The design for a curtain pole herein shown and described, which is, in general, cylindrical, alternate segments of the cylindrical surface being longitudinally reeded and alternate surfaces left of plain cylindrical form: substantially as set forth.

In testimony whereof I have hereunto set 35 my hand this 27th day of December, 1892.

LESLIE R. HARSHA.
